US00D994069S

(12) **United States Design Patent** (10) **Patent No.:** **US D994,069 S**
(45) **Date of Patent:** **** Aug. 1, 2023**

(54) **END PLATE SLING ADAPTER FOR FIREARM STOCK**

(71) Applicant: **Glock Technology GmbH**, Ferlach (AT)

(72) Inventor: **Patrick Nolte**, Ferlach (AT)

(73) Assignee: **Glock Technology GmbH**, Ferlach (AT)

(**) Term: **15 Years**

(21) Appl. No.: **29/735,640**

(22) Filed: **May 22, 2020**

(30) **Foreign Application Priority Data**

Nov. 25, 2019 (EM) 007297247-0001

(51) **LOC (14) Cl.** **22-01**

(52) **U.S. Cl.** **D22/108**

(57) **CLAIM**

The ornamental design for an END PLATE SLING ADAPTER FOR FIREARM STOCK as shown and described.

DESCRIPTION

FIG. 1 is a top, rear, left isometric view of an END PLATE SLING ADAPTER FOR FIREARM STOCK, showing the new design;

FIG. 2 is a bottom, front, left isometric view thereof;

FIG. 3 is a rear view thereof;

FIG. 4 is a front view thereof;

FIG. 5 is a right side view thereof;

FIG. 6 is a left side view thereof;

FIG. 7 is a top view thereof; and

FIG. 8 is a bottom view thereof.

1 Claim, 6 Drawing Sheets
